DEVICE FOR FORMING A BOW

Rose Eliasberg, 65 E. 96th St., New York, N.Y.

Filed Nov. 19, 1958, Ser. No. 775,013

1 Claim. (Cl. 2—154)

This invention relates to a device for forming bows.

It is the principal object of the present invention to provide a device that is adjustable on a scarf, neckerchief, belt or the like, and from which by the simple pulling of two portions thereof a bow can be formed.

It is another object of the invention to provide a device by which bows can be quickly formed of cloth material or apparel.

It is still another object of the invention to provide a quick method of forming a bow from wearing apparel in which the bow may be formed with the apparel in place upon the wearer.

It is a further object of the invention to provide a bow forming device that is simply formed of but two rings hinged together and easily manipulated for the insertion of the scarf, neckerchief or the like therethrough.

Other objects of the invention are to provide a bow forming device having the above objects in mind which is of simple construction, inexpensive to manufacture, of pleasing appearance, light in weight, consumes little space, decorative, durable, effective and efficient in use.

For a better understanding of the invention, reference may be had to the following detailed description taken in connection with the accompanying drawing, in which:

Figure 1 is a perspective view of the bow tying device according to one form of the invention,

Fig. 2 is a longitudinal sectional view of the bow tying device taken in line 2—2 of Fig. 1,

Fig. 3 is a perspective view of the device being applied to a neckerchief on a wearer, the same folded and the ends just started therethrough,

Fig. 4 is a perspective view of the bow tying device after the device has been pulled upwardly onto the neckerchief and turned to place the pull portions,

Fig. 5 is a longitudinal sectional view of the device after it has been turned on the neckerchief and as viewed on line 5—5 of Fig. 4,

Fig. 6 is a perspective view of the bow tying device when the portions of the neckerchief have been first pulled from the device to provide the loops of the bow,

Fig. 7 is a perspective view of the device with the bow fully formed,

Fig. 8 is a perspective view of the device in which the bow has been made in a kerchief which has been extended over the head,

Fig. 9 is a perspective view of the bow tying device when used on a sash or belt,

Fig. 10 is a plan view of the bow tying device construction according to another form of the invention, and

Fig. 11 is a longitudinal sectional view of the modified form of the bow tying device taken on line 11—11 of Fig. 10.

Referring now to the figures, 15 represents the bow forming device according to the first form of the invention which is constructed from two metal or plastic internal

2

rings 16 and 17 on which there has been respectively crocheted from thread of any color covers 18 and 19. These covers are joined and hinged together by crochet threads at 20 to provide a hinge connection therebetween so that the crocheted ring portions 18 and 19 can be folded over one another to have their respective openings 21 and 22 aligned with one another in the manner best illustrated in Figs. 3 and 5. A neckerchief 24 is placed about the neck and over the shoulders of the wearer as shown in Fig. 3 and two corners 25 and 26 are drawn together so that the device 15 having its ring portions hinged over one another with hinge 20 to the front and the openings 21 and 22 aligned, the device is started thereover. The next step is to pull the ends through the device 15 and elevate the device to a desired location that tightens the neckerchief about the neck. When in this location as shown in Fig. 4 the device is turned so that the outer sides of the ringface the front and the hinge is in the rear. In doing this two pull portions 25' and 26' present themselves. These portions are grasped by the two hands of the wearer and pulled outwardly together in the manner illustrated in Fig. 6 and can finally be opened to finally provide a full bow as shown in Fig. 7. The device will be used in the same manner to form a bow tight about the neck and under the chin as best shown in Fig. 8 to hold the kerchief tight over the head.

In Fig. 9 a sash or belt 27 is provided with a bow, in the same manner, the belt being drawn upon pulling the device onto ends 28 and 29 thereof and the bow formed by drawing outwardly pull portions 28' and 29' in the manner as above described.

In Figs. 10 and 11 there is shown a device formed of plastic as indicated generally at 30. This device 30 has two ring portions 31 and 32 that is joined together by a weakened hinge portion 33 that allows the rings to be folded upon one another for the purpose of permitting the ends 25 and 26 of a neckerchief to be easily threaded therethrough. The device will be used in the same manner after being drawn upwardly over the apparel to provide the pull portions 25' and 26'. The plastic device can be formed of semi-rigid plastic and made of any desired color and size.

It will be apparent that there has been provided a bow tying device which is easy to construct and apply to a neckerchief, scarf, or the like apparel, and from which a bow can be quickly made.

It should also be apparent that there has been provided a novel method of providing a bow assembly.

While various changes may be made in the detail construction of this device, it shall be understood that such changes shall be within the spirit and scope of the present invention as defined by the appended claim.

What is claimed is:

55 In combination, a cloth piece having free ends, two rings hinged together at their sides and being movable to overlie one another and separable to lie in a common plane, the free ends of the cloth piece being received through the two rings when said rings are overlying one another and loops drawn from the cloth piece when the rings are separated to lie in a common plane, whereby a simulated bow will be formed.
